UNITED STATES PATENT OFFICE

FRANK FERRARA, OF MEDFORD, MASSACHUSETTS, ASSIGNEE TO SHAWMUT ENGINEERING COMPANY, OF DORCHESTER, MASSACHUSETTS, A CORPORATION OF MASSACHUSETTS

CARRIER OR MEANS FOR PREPARING TUFT YARNS FOR A LOOM

Application filed March 11, 1929. Serial No. 346,017.

My present invention relates to manipulating or presenting series of yarns or threads, such as the tuft yarns for Axminster or other pile fabric looms, and aims to provide improved means for supporting and presenting such yarns or threads preparatory to and in the course of weaving and particularly in carpet manufacture. In certain respects the present invention is an improvement upon that disclosed in the co-pending applications of Edgar F. Hathaway Serial Nos. 290,916 and 317,728 filed July 7, 1928 and November 7, 1928, respectively.

In the drawing illustrating certain embodiments of the invention.

Fig. 1 is a plan of a yarn carrier or "tube frame" in position as in a threading or yarn placing machine, the central portion being broken away;

Fig. 2 is a partial plan, upon a larger scale and with parts removed or broken away, of one end of a yarn carrier or "tube frame" as in Fig. 1;

Fig. 3 is a vertical transverse section through the carrier or frame of Figs. 1 and 2, showing the yarns in threading position;

Fig. 4 is a part view in front elevation of the device of Figs. 1 to 3;

Figs. 5 and 6 are views corresponding to Fig. 3 of another embodiment of the invention, the carrier or frame being empty of yarns in Fig. 5, while the yarns are shown in threaded position in Fig. 6;

Figs. 7 and 8 are views corresponding to portions of Figs. 3 and 4, showing a further embodiment; and

Figs. 9 and 10 are part views also corresponding to portions of Figs. 3 and 4 respectively, illustrating still further means embodying the invention.

Referring more particularly to the drawing and first to Figs. 1 to 4, the tuft yarn carrier or tube frame there illustrated comprises a longitudinal supporting element or frame 1 which as shown is a tubular metallic member, but which may be otherwise formed, for example, as a wooden bar. Said carrier proper or frame 1 is adapted to support along it one or more tuft yarn spools 2, as by means of the bearings 3 for the spool

pintle 4. It is arranged for connection with the carrier chain of the loom in any suitable or usual manner, as by means of the chain-engaging members 5 and the hook-latches 6 at the frame ends.

The spool or spools 2 have wound upon them the series of threads, yarns, or yarn units 7 which, in their threaded position, extend across the frame 1. In position to cooperate with the yarns 7 the frame or carrier is provided with a longitudinal series of spacers, guides or barriers 9 for spacing and holding the yarns and, in the present instance, also serving as guides for the grippers of a loom during the weaving operation.

In the form shown in Figs. 1 to 4, for the purpose of illustrating the invention, said guides or barriers 9 and their connection with the frame may be substantially as disclosed in the co-pending application of Edgar F. Hathaway above mentioned. An attaching strip 10 is secured to the frame in any suitable manner, as by bolts or otherwise, and is formed with a flange 15 having a series of formations for receiving and positioning the adjacent ends of said guides or barriers, as by means of the tongues 17 formed on the latter.

Said attaching strip is also provided with a rib 18 of general U-shape in cross section, see particularly Fig. 3, having a series of slots 19, Fig. 2, similarly spaced as the holding formations of said flange 15. The individual guides or barriers are adapted to be received each in one of said slots 19, and are secured in assembled position as by means of a locking pin 20 passed beneath said U-shaped rib and through appropriately located openings in the respective guides.

The outwardly extending end portions of said guides are provided with means for preventing displacement of the positioned yarns in a direction lengthwise of the guides, said means in this instance being arranged to permit broadside threading or positioning of the yarns when desired. Each guide 9 accordingly is formed at or near its outer end portion with a laterally deflected barb-like nib 22, the forward edge of which, that facing the spool, is inwardly inclined, as indi-

cated at 23. As best seen in Fig. 4, said nibs 22 project laterally to or slightly beyond the next adjacent guide, thus providing below each nib a yarn passage 24. These passages 5 may be further defined by additional offsets or shoulders 25 below the nibs, as best seen in Fig. 3.

From the foregoing it will be understood that the frame or carrier 1 is provided with a series of yarn spacing members, barriers or guides 9 adapted to receive and hold a corresponding series of yarns or yarn ends in the desired spaced relation and to prevent lateral displacement of the yarns in any direction. In accordance with my present invention I provide means likewise to retain the yarns against displacement or disengagement in the direction of their length, to insure that they do not unthread, draw back 15 or run out to any undesirable extent subsequent to their placement upon the carrier, whether during movement of the latter from the threading machine to a place of storage or use, or during its use in the loom.

Referring still to Figs. 1 to 4 there is illustrated for said purpose an element, stop or tensioner 30 extending along the series of spacers or guides 9, either as a single piece or as a plurality of sections, desirably of 20 metal and somewhat resilient. Conveniently it comprises a metal strip arranged with one edge free and positioned beneath the nibs 22 of the series of guides, being secured along its opposite edge portion to the frame or carrier bar 1 in any suitable manner. As shown 25 it is removably attached by clips or holders 31, four of which appear in Fig. 1, distributed along the frame. As better seen in Fig. 2 said clips 31 are secured to the frame 1 in 30 any suitable manner, as by welding and each have a portion 32 raised sufficiently from the frame to receive the element or strip 30 beneath it and retain the same in operative position. Additional and generally similar 35 holding clips or stops desirably are provided at the opposite ends of said element, as indicated at 33, 33.

The free portion of said strip or element 30 in normal position approaches or contacts 40 the underface of the series of nibs 22. Being resilient it may be moved from said normal position sufficiently to permit the drawing in or placement of the yarns, thereafter returning or springing back so as to 45 firmly engage each yarn or yarn unit between it and the overlying nib of the respective guide 9.

In the form as shown in Figs. 1 to 4 said feed-stop means when in normal position 50 would block the series of yarn passages against entrance of the hooks or needles of a threading machine, which needles are to be projected through the yarn passages in the direction from left to right as viewed in Fig. 5 to engage the series of yarns and draw from

the spool or spools. The tensioning or feed-stop means is therefore so arranged that it may be depressed prior to the entrance of the needles, either manually or by means of a special depressing or clamping device associated with the threading machine, a portion of such device being indicated at D, Fig. 3 and being fully disclosed and claimed, together with the novel method of threading, in my copending application Serial No. 346,018, now Patent No. 1,847,055, granted Feb. 23, 1932.

It will now be understood that in accordance with my present invention the yarn carrier or tube frame and its series of separators or guides, which in Figs. 1 to 4 are of the open or side threadable type, is so constructed and arranged that the positioned yarns are retained not only against lateral displacement but against undesired withdrawal, retraction or running out, in a direction lengthwise of the yarns. In this manner it is assured that the entire series of yarns when once positioned and evened within the carrier will retain such position, each projecting an equal extent, without danger or disarrangement during manipulation of the carrier either prior to or during weaving. In this manner also I enable the use of substantially the entire length of yarns wound on the spools, avoiding waste. It will be noted that the above illustrative embodiment of the invention includes a tensioning or feed stop means which is common to the entire series of guides 9 and which is controllable similarly and simultaneously with respect to said entire series to open them for reception of the threading hooks or needles.

In Figs. 5 and 6 I have shown another embodiment of the present invention, parts not otherwise specifically mentioned being similar to corresponding parts in Figs. 1 to 4. The tension element, spring-strip or feed-stop means 35 in this instance is formed at its outer portion with a deflected, rounded, or cam portion 36, and an intermediate shoulder 37 between which and the overlying nibs 22 the respective yarns are adapted to be engaged and held against movement in the direction of their length.

Said element 35 may be of somewhat less lateral extent than in Figs. 1 to 4, its inner or flat portion being secured against the adjacent face of the frame or bar by clips 31, 32 similarly as in Figs. 1 to 4, or in any suitable manner. By reason of said cam portion this tensioning or feed-stop means is adapted for automatic opening for the reception of the yarn-engaging needles, one of which is indicated in dotted line at N in Fig. 5. The free ends of the needles themselves engage and cam down the portion 36 and upon retraction permit it to spring back into holding engagement with the yarns, substantially as seen in Fig. 6. Where the needles are of suffi-

cient strength and are properly guided, an automatically opening tensioner or feed-stop, such as that of Figs. 5 and 6 may be sufficient, or it may be employed in conjunction with other opening means, as in Figs. 1 to 4.

5 In Figs. 7 and 8 a further embodiment of the invention is illustrated, in which the feed-stop means is associated with a novel form of yarn carrier or tube frame. In this instance the carrier or frame comprises a bar or carrier proper 1, which may be similar as in the preceding figures. To this is secured as by means of a plurality of screws or bolts, one of which is indicated at 40, a longitudinal element, strip or series of strips 41 having an attaching portion 42 and a projecting guide portion including an upset or flange part 43 and a reversely bent lip 44. On said flange portion is provided a series of openings or slots 45 properly spaced to receive and position the series of yarn ends in the desired relation.

For retaining the several yarns against longitudinal displacement I have provided 25 a tension element or feed-stop 46 which is secured to the frame as by means of the bolts 40 previously mentioned and additionally or alternatively by clips 47 similarly as in the preceding figures. Said feed-stop device 46 30 in normal position projects upwardly and outwardly, terminating adjacent the yarn guiding formations 45 of the element 41 and having its free end beneath the reversed lip 44 of the latter. It will be understood that 35 in the threading of the carrier or tube frame of Figs. 7 and 8 said tension device or feed-stop is first depressed to permit entrance of the yarn engaging needles, this being done manually or mechanically as in Figs. 1 to 4. 40 Upon retraction of the needles said feed-stop springs up into position substantially as in Fig. 7 wherein it engages and holds the yarns against the lip 44, thus preventing their unintentional withdrawal, retraction or running out lengthwise. While the yarn spacing and guide means 41 has been illustrated 45 in Figs. 7 and 8 as having the yarn receiving formations closed, if desired it may be open at the side or top for lateral threading, 50 the yarns being retained against lateral displacement as by means of laterally projecting nibs similar to those of the guides 9 of Figs. 1 to 6. Also if desired the tensioner or feed-stop of Figs. 7 and 8 may be provided with a 55 cam portion for use as in Figs. 5 and 6.

In Figs. 9 and 10 there is illustrated a still further embodiment of my invention wherein the feed-stop or tensioning device is shown in combination with a yarn carrier or tube frame having yarn spacers or guides 50 of full tubular form. These may be secured along the bar or frame proper 1 in any desired or usual manner, as by soldering. At the inner or secured ends of the tubes is a 60 bead or rib 51 extending along the entire

series of tubes. As illustrated by way of example, it is provided by rounding up a strip or plate 52 which is attached to the bar or frame 1 and extends beneath the tubes 50 to constitute an attaching strip for the latter. 70 If preferred it may terminate short of the tubes and the latter may be attached directly to the bar 1, or said bead or rib may be otherwise formed.

75 In position to cooperate with said bead or rib 51 is a resilient tensioner or feed-stop element comprising one or more strips 53 extending along and above the series of tubes 50 and secured thereto as by soldering. Said element is extended downwardly and out 80 from one of the ends, herein the inner ends of the tubes 50 and terminates in a clip or clamp 54 opposite the bead or rib 51. The terminal edge of said element is preferably upturned substantially as illustrated as at 85 55. It will be observed that in this instance as in Figs. 5 and 6 the yarn engaging needles of a threading machine, which are passed through the several tubes in a direction from left to right as viewed in Fig. 9 will automatically engage with their forward ends and open the tensioner or feed-stop 53. During retraction of the needles said upturned portion 55, prevents them from catching on the tensioner, the latter, upon complete retraction of the needles springing into position to engage and hold the yarns between its portion 54 and the opposed bead or rib or raised part 51. Obviously the feed-stop or tensioner of Figs. 9 and 10 may be employed either with a yarn carrier or spacer of the full tubular form there illustrated or in connection with a side or slot-threadable similar element such, for example as disclosed in the patent to Bixby 1,670,434, dated May 22, 1928. It will be understood that the yarn-engaging or tensioning means of any of the several forms of my invention illustrated, while preventing unintentional withdrawal, retraction or running out of the yarns, does not prevent their purposed withdrawal when engaged and drawn on by instrumentalities of a loom or otherwise.

Having thus described certain illustrative embodiments of my invention it will be understood that the latter is not limited to the particular means shown and described herein, its scope being set forth in the following claims:

I claim:

1. In a tuft yarn carrier for looms, in combination with a frame or carrier proper adapted to support one or more yarn spools, a series of yarn guides along said frame to space a like series of yarns and guide them across the frame, a strip-like spring element along said series of guides adjacent one of their ends, supported at one side of the yarn paths and having a portion normally projecting into or across said paths, and means

at the opposite side of said paths against which said element is adapted to engage and tension the several yarns.

2. In a tuft yarn carrier for looms, in combination with a frame or carrier proper adapted to support one or more yarn spools, a series of yarn guides along said frame to space a like series of yarns and guide them across the frame, an elongated resilient strip having one longitudinal edge portion secured along one side of said series of guides and having its opposite or free side extended toward the yarn-entrance portions of the yarn guides, and opposed means against which said strip is adapted to tension or restrain the several yarns positioned by said guides.
3. In a tuft yarn carrier for looms, a frame adapted to support one or more yarn spools, a series of yarn spacing and guiding formations along said frame, and a tensioner in the form of a metal strip having a longitudinal portion extending externally along said series of formations and having an open or threading position and a holding position in which it engages the yarns positioned in said formations to prevent undesired withdrawal, retraction or advancing of the yarns.
4. A tuft yarn carrier for looms comprising, in combination, a frame, a plurality of yarn guides distributed along the frame, a strip of spring material extending along said frame in position to retard lengthwise movement of the several yarns positioned by said plurality of guides, said means being movable out of said yarn-retarding position to facilitate placing of the yarns with respect to said guides, and a cam element on said strip for moving it out of retarding position.
5. A tuft yarn carrier for looms comprising, in combination, a frame, a plurality of yarn guides distributed along the frame, and common means along said frame for uniformly tensioning the plurality of yarns positioned by said guides, including a cam-like portion whereby said means may be opened or moved away from the path of the yarns by yarn-placing instrumentalities thereby to facilitate placement of the yarns with respect to the guides.
6. In a tuft yarn carrier for looms, in combination with a frame or carrier proper, a series of yarn guides along said frame to space a like series of yarns and guide them across the frame, an elongated element secured along one side of said series of yarn guides, externally thereof and having its opposite or free side extended toward the yarn-entrance portions of the yarn guides, and opposed means against which said element is adapted to tension the several yarns positioned by said guides, said free side of said element having its outer edge portion deflected toward the plane in which its other side is secured, for cooperation with yarn-placing instrumentalities.

7. A yarn carrier for looms comprising, in combination, a frame or supporting bar, a yarn guiding element secured to said frame and having a longitudinal flange projecting transversely of the latter and approximately perpendicular to the path of the yarns, and a series of substantially continuous-walled yarn receiving and guiding formations along said flange.

8. A yarn carrier for looms comprising, in combination, a frame or supporting bar, a yarn guiding element secured to said frame and having a longitudinal flange projecting transversely of the latter, a series of yarn receiving and guiding formations formed in and along said flange, and yieldable means engageable with said flange at or adjacent the several guiding formations to tension the yarns therein.

9. A yarn carrier for looms comprising, in combination, a frame or supporting bar, a yarn guiding element secured to said frame and having a longitudinal flange projecting transversely of the latter, a plurality of transverse yarn passages along said flange, laterally projecting means along the outer portion of the flange, and yieldable means to tension the several yarns positioned in said passages by engaging them against said laterally projecting means.

10. In a yarn carrier or tube frame for looms, a frame or supporting bar, a series of transverse yarn guides therealong providing yarn passages or guide formations having yarn intake ends and yarn discharge ends, and a yieldable strip-like element secured along and above said series of guides in their horizontal position and having a free side portion projecting downwardly into or across the yarn paths at one end of said guides thereby to engage and tension the several yarns.

11. In a yarn carrier or tube frame for looms, a frame or supporting bar, a series of transverse yarn guides therealong providing yarn passages or guide formations having yarn intake ends and yarn discharge ends, a yieldable strip-like element secured along and above said series of guides in their horizontal position and having a free side portion projecting downwardly into or across the yarn paths at the intake ends of said guides, and means against which said projecting portion of said element is adapted to tension the yarns.

In testimony whereof, I have signed my name to this specification.

FRANK FERRARA.
